Michael H. Steele

UNITED STATES PATENT OFFICE.

MICHAEL H. STEELE, OF GREENSBURG, PENNSYLVANIA.

FURNACE.

SPECIFICATION forming part of Letters Patent No. 414,826, dated November 12, 1889.

Application filed April 13, 1889. Serial No. 307,205. (No model.)

To all whom it may concern:

Be it known that I, MICHAEL H. STEELE, of Greensburg, county of Westmoreland, State of Pennsylvania, have invented or discovered 5 a new and useful Improvement in Furnaces; and I do hereby declare the following to be a full, clear, concise, and exact description thereof, reference being had to the accompanying drawings, making a part of this specification, in which (like letters indicating like parts)—

Figure 1 is a view, chiefly in longitudinal section, of my improved furnace, showing the boiler directly above the furnace. Fig. 2 is 15 a cross-section taken on the line $x-x$ of Fig. 1, and Fig. 3 is another longitudinal section showing a mode of construction which locates the boiler farther in the rear of the furnace.

My present invention relates to the same 20 class of smoke-consuming furnaces for which Letters Patent of the United States No. 393,182 were granted to me November 20, 1888; and it consists in an improved mode of construction by which the products of combustion arising from the fire are retarded in 25 their movements toward the exit, and are retained in combustion-chambers (in whole or in part, beneath and around the boiler) subject to the action of the flame and heat until 30 the combustible gases are consumed.

I have found by experience that a considerably higher degree of heat is required to consume the gases arising from the fuel than is needed to consume the smoke alone, and 35 these gases furthermore contain valuable properties for heating purposes, so that my present mode of construction attains the additional advantage of much more effectively consuming the resulting gases, which are 40 driven off by the first contact of the fuel with the fire, and I am thereby enabled to largely increase the heating capacity of the furnace and work an additional economy in fuel. The method of construction by which I accomplish 45 this purpose is herein fully pointed out and explained by reference to the drawings.

I do not wish to limit myself to any particular arrangement of the boiler with relation to the furnace; but I have shown in Figs. 50 1 and 3 what I consider the preferable mode of arrangement.

C is the front wall of a furnace as ordina-

rily constructed, through which is the fuel-door D, having in connection therewith a shelf b, upon which the fuel is placed before 55 being pushed into the furnace. Below this is another opening e, to allow the use of a poker in cleaning the grate, and still further below at E are doors to admit draft. At d in Fig. 3 is shown an additional opening for draft. 60 At the rear wall of the furnace at N are shown doors to admit of access to this end of the boiler and furnace.

L is the grate, which is of ordinary form, and c is also an inclined grate leading from 65 the shelf b to the main grate.

M is an ash-pit, and J is another one.

F is the first in a series of combustion-chambers, arranged consecutively beneath or partly beneath and partly in front of the 70 boiler. A is the back wall of this first chamber. Leading from the grate to the back wall are two short walls a and a, between which and downward through a connecting-passage G, leading to the next chamber H, is the only 75 means of exit for the products of combustion arising from the fire on the grate. These guide-walls a a form a duct for the draft, which tends to draw the flame from the fire to the point of exit, where it plays strongly upon 80 the smoke and gases, which descend to the same point in seeking vent. This passage-way G is regulated by damper K, to which is attached a counterbalanced weight.

The successive combustion-chambers, 85 through which the heat, flame, and gases arising from the fire must successively pass, are shown at H, H', and H''. These chambers communicate with each other by means of the openings f f, placed, preferably, at or near 90 the floor of the chamber. The object in so placing the openings f f, as well as in lowering the passage G, is to prevent the products of combustion generated in the first chamber from passing rapidly and directly from one 95 chamber to another and to so retard them as to give large opportunity for their entire consumption.

The partition-walls A, I, and J between the respective chambers are made to fit snugly 100 against the boiler at the top, so as to prevent any escape except at the openings near the bottoms of the chambers. The openings between the chambers should be of sufficient

size to afford a good draft, but not large enough to permit the contents of the chamber to escape too easily, as it is in the retarding and retaining in the several combustion-chambers of the products of combustion which are generated in the first chamber that the merit of my invention lies.

The precise number of chambers to be used is not material; but I have found the best results are obtained by the use of at least four consecutive chambers.

The operation of my improvement, which will be apparent, is as follows: Upon the introduction of fuel in the usual way into the furnace it of course comes in contact with the fire and flame on the grate in the first combustion-chamber F, and it is here that the principal combustion occurs. The heated air and the products of combustion naturally rises to the top of the chamber, but, there being no chance to escape here, whatever is not consumed is finally forced out by the aid of the draft through the passage-way G from the lower rear of the chamber into the secondary combustion-chamber H. In passing between the walls *a a* and into the passage-way G the unconsumed smoke and the consumable gases are brought into direct contact with the flames from the fire, which is naturally most intense and concentrated most strongly at this point, and I find in practice almost all the dense smoke here disappears and is consumed. The heated air in the secondary chamber and such gases as remain unconsumed are here subjected to substantially the same process as in the first chamber and finally escape through the opening *f* into the succeeding chamber H'. Not even yet is the product of combustion allowed to escape into the chimney, but it is here retained for further action by the heat from the fire until further possible combustion takes place, when in due time it makes its way into the final chamber H'', from which it escapes into the boiler-flues or chimneys in the usual way. Thus the combustible material is utilized to the fullest practicable extent and all the valuable heating

properties of the fuel are extracted. The practical result is that the dense carbon is substantially all consumed, and the resultant which finally escapes from the chimney is almost or quite colorless, so that the combined effect of my improvement is to not only abolish the smoke nuisance, but to greatly increase the heating capacity of the furnace.

Another object which I attain is in this—that not only does my mode of construction permit of a much more complete consumption of the products of combustion themselves, but, by means of the successive chambers and the retarding-walls between them, the heated air itself is retained in contact with the surface of the boiler for a longer period than would otherwise be the case, and thus the same degree of heat is made more efficient.

Having thus described my invention, I claim herein and desire to secure by Letters Patent of the United States—

1. The improved furnace consisting of the combination, with the boiler, of the series of combustion-chambers F H H' H'', arranged consecutively, chamber F having draft-opening G at its lower rear end and guides *a a* leading thereto, by means of which the draft and the products of combustion are carried out of said chamber, the whole constructed and arranged substantially as and for the purposes specified.

2. In combination with a boiler and a series of combustion-chambers, the chamber F, having lower rear-draft opening and guide-walls *a a* leading thereto, substantially as and for the purposes set forth.

3. The combination of a boiler and a series of combustion-chambers in which is chamber F, having lower rear draft-opening G, guide-walls *a a* leading thereto, and a passage-way from said chamber to the succeeding chamber, located below the level of the grate, arranged and operating substantially as and for the purpose set forth.

MICHAEL H. STEELE.
